METHOD AND MEANS FOR PRODUCING GAS

Hiram J. Carson, Omaha, Nebr.

Original application April 8, 1929, Serial No. 353,576. Divided and this application March 14, 1934, Serial No. 715,401

5 Claims. (Cl. 48—204)

This invention relates to the production of combustible gas in blue and carburetted water gas sets, the principal objects of the invention being to effect economies in such production by 5 improvements in the methods and means employed.

This application is a division of my copending application 353,576 filed April 8, 1929, for Improvement in methods of and means for producing gas, now Patent 1,953,848, granted April 3, 1934, and the invention combines certain novel features with some of those disclosed in my earlier co-pending application 199,572 filed June 17, 1927, now Patent 1,952,654, granted March 27, 15 1934, and comprehends:

Improved methods for gasifying bituminous fuel in a water gas generator; the recovery of liquid hydrocarbons and ammonia from bituminous fuel.

20 When bituminous fuel is used in a generator of the usual type having the blue water gas and air blow gas offtakes at the same level, volatile matter from the fuel is driven off during the gas making period and is also driven off during the air blasting period. Also, in the usual up and down run method of operation in which steam for gas making is alternately admitted above and below the fuel bed, the hydrocarbons distilled from the fuel during the down run portion are passed through the hot zone of the generator fuel bed and broken down into mostly carbon and hydrogen.

With bituminous fuel, such as coal, used as 35 generator fuel, the invention contemplates a method wherein an upper carbonizing zone and a lower incandescent or generating zone are maintained in a generator. The air blast gases from the lower zone, with or without the secondary combustion thereof, may be used for externally heating the upper zone or a portion of such blast gases may, when desired, be passed through the upper carbonizing zone for internally heating the fuel therein. Part or all of the hot blue 40 water gas from the lower incandescent zone may be passed through the fuel in the upper zone for devolatilizing the fuel and any remaining portion of the blue gas drawn off separately for enrichment with liquid hydrocarbons. With fuel containing little or no volatile matter, such as coke, the invention contemplates passing part or all of the blue water gas from the lower zone through the newly charged fuel in the upper zone to thereby preheat such fuel before it descends into 45 the lower water gas generating zone.

The improved method may also be carried out when relatively no volatile fuel is used for generator fuel, with part or all of the blue gas drawn off through the upper gas offtake, thereby preheating the newly charged fuel before its descent into the lower water gas generating zone.

In carbonizing fuel in water gas generators by internal and/or external heating as above described, difficulties are experienced with some fuels which on heating swell, arch or hang in 10 generators and form a plastic zone through which gases are passed with difficulty if at all.

The volatile matter of bituminous fuels is of varying composition and distillable at different temperatures. The volume and quality of the 15 volatile matter given off varies with the temperature and time of heating.

When the volatile matter distilled off at relatively higher temperatures passes through cooler fuel, some or all of it is usually condensed on 20 the cooler fuel. This condensate encases the lumps or particles of fuel in a liquid envelope often of a plastic nature which is not again vaporized until the fuel passes into a zone of higher temperature. Meanwhile the coal lumps 25 and particles contain volatile matter distillable at relatively low temperatures, which being partially or wholly confined within the liquid envelope causes the fuel to swell.

If the volatile matter evolved from bituminous 30 fuel as it is heated is removed from contact therewith substantially as it is formed under temperature and partial pressure conditions above the condensation point, the time required for distilling off the volatile matter at any given temperature is greatly reduced; cracking of the hydrocarbons so evolved is avoided and the condensable portion of these hydrocarbons may be recovered in liquid form. With the hydrocarbons drawn off as formed and cracking avoided, the 35 heat required for carbonization is substantially less.

If swelling or sticking coals are preheated for a time at 900 deg. F. more or less, the swelling 40 properties and tendency toward the formation of a plastic zone is thereby reduced.

The invention contemplates the devolatilization of the fuel by the heat in the blue gas and any undecomposed steam mixed therewith passing through it at relatively higher temperatures 45 than are obtained in usual practice when desired and supplemented by other means and methods more fully hereinafter described.

The invention also contemplates preheating 50

the coal to prevent sticking and the formation of a plastic zone.

The invention contemplates the distillation of the fuel under controllable temperature conditions to permit the evolving and recovery of condensable hydrocarbons of varying qualities as desired, as hereinafter more fully described.

In the manufacture of carburetted water gas, the invention contemplates passing a part of the water gas through the carbonizing chamber and the remaining portion in desired volume through a carburetted chamber for enrichment therein by hydrocarbon vapors from liquid hydrocarbons.

The invention also contemplates the admission of steam in the lower zone of the carbonizing chamber for the formation of ammonia and/or blue gas with such formation furthered by the presence of lime or limestone when charged with the fuel for the additional purpose of fluxing the ash.

The invention contemplates the maintenance of optimum temperatures for ammonia formation in the carbonizing chamber when ammonia recovery is desired.

The invention also contemplates the formation of methane in relatively large volume because of the catalytic effect in such production by any lime or limestone charged with the fuel as a fluxing agent for the ash.

Other objects of my invention will more clearly appear from the description and claims herein-after following.

In the drawings forming a part of this specification, I have illustrated suitable apparatus, with certain indicated modifications under different conditions, which may be employed in the practical carrying out of my improvements in water gas generation. In said drawings—

Fig. 1 shows a carburetted water gas plant in elevation and partly in section suitable for carrying out my improvements.

Fig. 2 is a partial plan view of the structure shown in Fig. 1.

Fig. 3 is an enlarged fragmentary vertical section of a carbonizing chamber in the generator shown in Fig. 1.

Fig. 4 is a sectional view of the generator on the line 4—4 in Fig. 1, showing a restricted and elongated base and other features.

Fig. 5 is an enlarged fragmentary vertical sectional view showing the details of construction of an air tuyère, tuyère header and air inlet valve in the lowermost air blast level of the generator in Fig. 1.

Fig. 6 is an elevation of a carburetted water gas plant partly in section with modifications as hereinafter fully set forth.

Figs. 6 and 7 are similar to Figs. 1 and 2 with the gas superheater omitted and the carburetted and gas superheating functions combined in a carburetted-gas superheating chamber, with corresponding modifications.

Fig. 8 is an elevation of a carburetted water gas plant partly in section, with generator and carburetted-gas superheating chamber as in Fig. 6, with two additional chambers each of which is used for superheating steam and preheating air.

Fig. 9 is a plan view of the carburetted-gas superheating and steam superheating-air preheating chambers of Fig. 8 with some details of construction.

Fig. 10 is a view in elevation and partly in section of a blue water gas plant consisting mainly of a generator and two regenerating chambers, each of which is used for superheating steam and

preheating air as in Figs. 8 and 9 with the carburetted-gas superheating chamber omitted and corresponding modifications.

Fig. 11 is a plan view showing the steam superheating-air preheating chambers and their connections with a fragmentary plan view of the generator.

The apparatus may now be described in detail.

In Fig. 1 the gas generator 12 is shown in section having mainly two zones, the lower zone 17 being the water gas generating zone and containing mainly incandescent fuel. The upper zone contains a carbonizing chamber 18, which is charged with fuel, such as bituminous coal, and an ash fluxing material, such as limestone, when desired through any suitable charging device as 19. Air blast inlet means are provided as shown at levels 20, 20a, 20b, and 20c. Steam inlet means are similarly shown at level 21. The carbonizing chamber has an annular passage 20 around it of a relatively large area at 22 to lower the velocity of the gases leaving the incandescent fuel and reduce or avoid the carrying along of fine fuel particles in the gases.

The annular passage is preferably narrowed at 23 to increase the velocity of the gases and heat transfer to the carbonizing chamber. The generator wall lining of the passageway 22 and 23 is preferably made of heat radiating material to supply radiant heat to the carbonizing chamber.

The annular passageway 22 and 23 is preferably enlarged at 24 to reduce the velocity of the gases at this point and to further a uniform passage of the gases around the carbonizing chamber.

The gases pass from 24 into the carburetter through a conduit 25 shown with a valve therein which may be dispensed with as hereinafter described.

The wall of the carbonizing chamber 18 is preferably made of heat resisting metal to permit a relatively high rate of heat transfer therethrough but when secondary combustion of the air blow gases is effected in 22 by air admitted as at level 20c, that portion of the chamber wall exposed to unduly high temperatures may be made of a suitable refractory material.

The carbonizing chamber preferably contains an assembly 26 in the center thereof. This assembly is shown enlarged in Fig. 3 and is more fully described hereafter.

An inlet 27 for steam or air is shown near the bottom of the carbonizing chamber, supplied by a vertically disposed conduit 28 passing through the assembly aforesaid and fed and supported by a pipe 29. An assembly cap or valve 30 adjustable as by a cable 31 for regulating the division of flow of gases through the assembly 26 and the fuel is shown.

The carburetter 13 has a combustion chamber 26, with the usual valved oil admission means 27 (which may be dispensed with) opening into it, also a zone of heat absorbing material 28, with an oil admission zone 29 below with valved oil inlets as 29a and 29b and preferably with a lower zone of heat absorbing material 30.

The bottom of the carburetter is in open connection with gas superheater 4, which is of the usual type and filled with heat absorbing material such as checker brick.

The gas superheater is shown with the usual stack valve 32 and a closable gas outlet 33, and an alternate valved gas outlet 34 leads to a con-

denser 35 having a gas outlet 36, with a vacuum pump 37 installed therein.

The usual stack valve 32 on the gas superheater is shown in the usual manner for use 5 when desired.

The top of the gas superheater opens into the steam superheating chamber 15 through a valved conduit 38 into the combustion chamber 39.

The steam superheater is filled with heat absorbing material 40 and has a passageway 41 opening through a valved conduit 42 into the combustion chamber 43 of air preheating chamber 16, and similarly into a similar combustion chamber in air preheater 16a as indicated in Fig. 2. The air preheating chambers are filled with heat absorbing material 44 and have an upwardly extending passageway 45 leading to stack valves 46 and 46a.

The generator is shown with a solid hearth 47 preferably sloping toward a slag discharge opening 48 which is normally closed by any suitable means such as fire clay.

A second slag discharge opening 48a is shown at a higher level for use when iron or metallic ore is charged with the fuel as a fluxing agent. The metal may be drawn off at the lower level 48 with the slag drawn off at the higher level 48a.

The pipe 49 opening into the air inlet at level 20 indicates an admission means for gas or oxygen 30 for mixing with the air to effect combustion or raise the temperatures in the fuel bed at this level as desired for slagging the ash. This connection 49 may also be used for supplying the fluxing material into the air blast.

Another opening into the fuel bed at any suitable level, as at 50, is shown for the introduction of fluxing material as desired.

The generator is equipped with a valved gas outlet 51 in the top of the carbonizing chamber 48 for the withdrawal of the coal distillation gas and vapors and any other gases mixed therewith to such further point in the apparatus as is desired.

As further shown in Figures 1 and 2:

An air supply pipe 52 is connected to valved inlets 53 and 53a to the air preheaters. The valved preheated air outlets 54 and 54a are connected into a header 55 supplying the preheated air distributing pipe 56. The latter pipe supplies combustion air to the air preheating chambers through valved inlets 57 and 57a, to the steam superheater through 58, to the carburettor through 59 and to the generator through valved inlets and air tuyère headers supplying tuyères 127 at levels 20, 20a, 20b, 20c and air admission means 127 through valved connection 60 and pipes 129 and 128.

The air preheaters may be bypassed through a valved bypass 52a directly into air distributing pipe 56.

Steam is supplied from a source not shown through a valved inlet 61 into steam superheater 15. The valved superheated steam outlet 62 opens into the superheated steam distributing pipe 63 which supplies the carburettor when desired through valved connection 64 and the generator through valved inlet 65 and pipes 129 and 128 leading to opening 27 and to steam tuyère openings at level 21 through a valved inlet and tuyère header as shown.

In Figure 3 an assembly is shown in a fragmentary section of the carbonizing chamber 18 with air or steam admission means 127 supplied by pipes 128 and 129 passing through the assembly as previously described.

This assembly is preferably made of a series of open cylinders or cones 66 of any desired form with the bottom of each cylinder projecting over and below the top of the next lower cylinder, thus forming a protective skirt around the upper open end of the next lower cylinder to prevent fuel falling therein and to provide annular openings 67 for the escape of volatile matter from the fuel into the open passage through the series of cylinders as indicated by arrows.

The assembly cap 30 is adjustable by cable 31 to regulate the division of flow of gases through the assembly and the fuel.

Figure 4 shows the restricted and elongated section at the level 4-4 of Figure 1 with the tuyères opening into the long sides at 67 and with the interior accessible through doors 68 and openings 69 which are normally filled with removable refractory material. The lowermost air blast tuyère header is indicated by 71 and the steam tuyère header at 70.

Figure 5 shows a fragmentary section of the generator wall with an air blast tuyère therein. The tuyères at each level are supplied by tuyère header pipes 71 which are supplied by the air 25 distributing pipe through valves 72. The tuyère nose 73 is shown projecting beyond the generator wall and water-cooled by water entering through pipe 74 and discharging through 74a.

The pipe 49 is shown inserted in the tuyère 30 through which combustible gas or oxygen may be introduced for mixing with the air and assisting in combustion at the lowermost air blast level. Fluxing material in powdered form may also be similarly admitted into the blasting air.

In Figure 6 and the partial plan view thereof in Fig. 7 a carburetted water gas plant mainly similar to that shown in Figures 1 and 2 is shown with the gas superheating chamber of Figure 1 omitted and the functions of the carburettor and 40 gas superheater combined in one chamber as 13' with the gas outlet in its bottom leading through valved conduit 33' to such other point in the apparatus as desired or, when lower absolute pressures in the carburettor are desired, through 45 valved connection 34' to condenser 35 and vacuum pump 37 and thence to such other point as is desired through outlet 36.

The air and steam connections and inlet and outlet connections to the steam superheating and 50 air preheating chambers are all substantially as shown and described in connection with Figures 1 and 2, with modifications to suit the omission of the gas superheating chamber of Figure 1 with a steam connection 61a for by-passing the steam 55 superheater when desired. These connections are all disposed so the blow gases in heating these chambers will always pass downwardly and the air and steam in being preheated will always pass upwardly through the heat absorbing material. 60 The stack valves of Figure 1 are replaced in the construction of Figures 6 and 7 by valves 146 and 146a leading to a common stack 75.

In Figure 8 and the partial plan view thereof in Figure 9, a gas generator 12 with a valved 65 connection 25 to carburettor-gas superheating chamber 13', both similar to the units in the previous figures, are shown with the chamber 13' connected directly to two regenerative chambers, each of which are alternately heated by the air 70 blast gases and used for superheating steam and preheating air. Valved air supply pipe 52' and steam supply pipe 61' alternately supply air and steam to chambers 16' and 16a' through a common inlet header and valved inlets 53' and 53a'. 75

The preheated air leaves these chambers through valved outlets 54' and 54a' connected into air distributing pipe 56' and thence to supply combustion air to these chambers and the generator in a similar manner as before described. The superheated steam leaves through outlets 62' and 62a' to distributing pipe 63' and thence as before described. The gas outlet 33' leads to other apparatus or vacuum pump as before described.

Steam and air inlets 61a' and 52a' respectively are provided for bypassing the regenerative chambers when desired.

In Figure 10 and the partial plan view thereof in Figure 11, a generator is shown in combination with two regenerative chambers each of which is alternately heated by the blow gases and used for superheating steam and preheating air as in Figures 8 and 9. This is essentially a blue gas plant and similar to that in Figures 8 and 9 with the carburetting-gas superheating chamber 13' omitted and corresponding changes to suit this omission.

Obviously the inlet and outlet connections and passages to the different chambers in the different figures may be varied from those shown. The invention contemplates such a disposition of these that the heating gases will pass downwardly and the air and steam will pass upwardly through the heat absorbing material.

The operation of the apparatus is as follows, particular reference being had to the apparatus illustrated in Figures 1 to 5:

A fire is kindled on the generator hearth 47 and the generator is filled with fuel (preferably coke at the start), which is replenished with preferably bituminous coal thereafter through charging opening 19.

All valves are closed save stack valve 46a and valves 42a, 38, 25, 53, 54 and at air blast level 20. Air is admitted through 52, 53, 16, 54, 55, 56 to air blast level 20. The gases resulting from the combustion of the fuel pass upwardly through the fuel and passageways 22, 23 and 24 and successively through the carburetter, gas superheater, steam superheater and thence through air preheater 16a to the stack.

As the air blasting progresses and the fuel bed in the gas generator becomes heated, carbon monoxide is formed in increasing volume. This carbon monoxide may be burned by air admitted through the opening of valves at any level as 20a, 20b, 20c, as desired, but in starting and to heat the apparatus throughout it is preferably first burned by air admitted to the carburetter through valved inlet 59. When the carburetter is sufficiently heated or when it is desired to further heat the steam and air preheating chambers, combustion may be effected in these by air admitted through 58 and 51a, as desired.

The generator fuel bed is preferably continuously blasted throughout the period at level 20 and the CO content of the gas leaving the fuel bed limited by effecting combustion therewith through air admitted selectively as desired at the higher levels, thus building up a relatively thick high temperature fuel bed with a definite limitation of the CO produced, as by this method the fuel in the bottom zone is mostly consumed with a reduction to ash and slag there and the heat therefrom stored in the fuel at higher levels with less consumption of fuel and reduction to ash at the higher levels.

The fuel bed may also be blasted at the lowest level for a certain time and then as the

fuel becomes hot and CO is produced in the maximum amount desired, the blasting may be discontinued at this level and begun at a higher level thus bypassing the underlying zone of hot fuel, then again discontinued and begun at a still higher level and so on until a fuel bed of the desired temperature and thickness is built up.

With the fuel bed hot and the apparatus at the desired temperature the air blast is cut off and all valves save 25 are closed. When the gas outlet 33 is used and the condenser 35 and vacuum pump 31 dispensed with, the valve 25 may be dispensed with. Outlet 33 communicates with a seal separator, or other apparatus, not shown, and is opened.

Steam admitted through 61 passes down through passageway 41 and up through 40, where it is highly superheated, then passes through valved outlet 62, pipe 63, through inlet valves, tuyère header and tuyères at level 21 to 20 the fuel bed. The steam leaves the tuyère openings at a relatively high velocity and through a plurality of openings so as to penetrate the fuel bed uniformly.

The steam also enters the fuel at a sufficient distance above the lower zone of intensely hot fuel so as to bypass it without an appreciable cooling action on any liquid slag in the lower zone.

The freezing of the liquid slag at the lower level 30 is further avoided in supplying the steam to the fuel bed superheated at a temperature relatively near to or above the freezing temperature of the slag.

The steam in passing through the relatively thick high temperature fuel bed is decomposed with the formation of carbon monoxide and hydrogen or blue gas. A portion of the blue gas so formed enters the bottom of the carbonizing chamber 18, sweeps through the fuel in the lower portion thereof and with any volatile matter therefrom a portion enters the bottom opening of the assembly 26. The remainder, sweeping up through the fuel, further devolatilizes it and either entering the assembly through annular 45 openings as at 67 in Figure 3, or passing up through the fuel, passes out through upper off-take 51.

The cap 30 on the assembly may be raised or lowered, thus adjusting the flow through the fuel 50 and the assembly as desired. The valve 51 is also adjustable to regulate the volume of blue gas passing through the carbonizing chamber.

The blue gas and any coal gas and vapors mixed therewith in passing through the cylinders 55 of the assembly produces a vacuum effect which draws the gas from the fuel being carbonized in through the annular spaces as 67 into the stream of gas.

The gas and vapors are accordingly withdrawn 60 from the fuel substantially as evolved and mixing with the blue gas leave the assembly through 30 and pass out through 51.

The heat for carbonizing the fuel is supplied by the sensible heat of the blue gas and any undecomposed steam passing through it and the assembly and is supplemented by:

(a) The heat in the blow gases passing around the carbonizing chamber with or without the secondary combustion of the blow gases effected by 70 air admitted at level 20C as desired for heating said chamber.

(b) The use of additional amounts of excess steam preferably superheated as hereinafter described by the heat in the blow gases.

(c) Passing part of the blow gases through the carbonizing chamber and using the sensible heat thereof and/or

(d) Admitting air and/or oxygen in the lower portion of the carbonizing chamber through 127 for effecting secondary combustion of any blow gases passing therethrough as described above in (c).

(e) Admitting air and/or oxygen in the lower portion of the carbonizing chamber through 127 for combustion and the liberation of heat thereby. In this case the burned gases may be taken off through 51 mixed with the distillation gases but the air or oxygen is preferably admitted 15 during the blasting period with the distillation gas outlet restricted so the burned gases will pass out through the bottom of the carbonizing chamber into 22 and mix with the blow gases, thus preventing dilution of the distillation gases. The 20 carbonization temperature may accordingly be varied and controlled by the above methods of heating.

The hydrocarbon vapors are drawn off substantially as formed through assembly 26 and outlet 25 51 with a recovery of the condensable hydrocarbons in liquid form when desired, with little or no difficulty with the fuel arching or sticking during the carbonization process.

The remaining portion of blue gas and any 30 undecomposed steam passes through 22, 23, 24, 25 into carburetter 13 and downwardly through the highly heated heat absorbing material 28 into oil admission zone 29. The hot blue gas mixes with oil sprayed into 29 through 29a, and 29b, 35 and is cooled thereby.

The heat in the blue gas and steam and that radiated by the walls and refractory material adjacent to 29 brings the oil particles to the desired temperature for cracking and formation 40 of stable hydrocarbon gases. In the passage of the gases and any uncracked oil particles through 30, and the heat absorbing material in 14, the cracking is completed and the carburetted gas passes out through offtake 33 with the valve 45 therein adjusted as desired so that with valve 51, the division of flow of gas between carbonizing chamber and carburetter is additionally regulated. Steam may be admitted to the carburetter when desired through valved inlet 64.

50 When absolute pressures lower than the pressure in passageway 24 are desired in the carburetter, the valve 33 is closed or omitted with opening blanked, the valve 34 is opened and vacuum pump 37 operated.

55 In this case the valve 25 is partly closed to restrict and regulate the flow of gas to the carburetter. The oil is sprayed in as before and the resultant gas drawn off through the condenser and vacuum pump to such further point in the 60 apparatus as is desired.

A controllable amount of air enriched with oxygen when desired at the air blast level 20 may be admitted during the gas making period to maintain a sufficiently high temperature at 65 this level for liquefying the slag.

As the gas making period progresses, the fuel bed temperature falls and the chambers cool. When it is impracticable to continue the period, all valves except 25 are again closed and valves 70 46, 42, 38 are opened.

Air is then admitted to the air preheater 16a through 53a and there preheated and then passed through 54a, 55, 56 to the generator carburetter, steam superheater, air preheater 16 and on 75 through stack valve 46 as previously described.

During the air blasting period the valve 51 is adjusted to permit the withdrawal of coal gases and vapors evolved meanwhile with the inclusion therein of a limited amount and preferably none of the blow gases.

Steam may be admitted through valved inlet 61a, 63, 65 and 27 to blanket the entrance of blow gas into the carbonizing chamber and for the formation of blue gas and/or ammonia and to assist in carrying off the coal gases and vapors through offtake 51 as previously described for the blue gas during the gas making period.

When the generator fuel bed, carburetter and regenerative chambers are sufficiently hot, the air blast is stopped and the gas making period 15 resumed as before described.

The operation of the apparatus in Fig. 6 is carried on in a similar manner as described for Figures 1 and 2, with account taken of the omission of the gas superheater 14 of Fig. 1.

The apparatus in Figures 8 and 9 is operated in like manner with account taken of the use of each of the two regenerators 16' and 16a' for superheating steam and preheating air.

In Figures 8 and 9, and assuming the apparatus to be heated and ready for continuous operation, with all valves closed except 52', 53', 54' and at level 20, and with 25, 42a' and 46a' open, air passes through and is preheated in 16' thence through 54' and 56' to the generator, 30 carburetting-superheating chamber, regenerator 16a' and thence to stack through 46a''. This blasting is controlled and varied at the different generator levels and in the other chambers as previously described. When the desired temperature is reached in the generator and other chambers, the air blast is discontinued and all valves except 25 are closed. Steam is now admitted to regenerator 16a' through 61' and 53a' and superheated therein, passes through 62a' 40 into distributing pipe 63' for use as previously described, the gas outlet 33'' leading to vacuum pump or other apparatus as before described.

When the fuel bed and apparatus is cooled to such an extent that it is no longer practicable 45 to continue the gas making period, steaming is discontinued, all valves are closed except 25. Valves 52', 53a', 54a' and at level 20 in the generator and also 42', 46'' are open. The air passes through and is preheated in 16a', and then passes 50 therefrom to level 20 in the generator fuel bed. The gases therefrom pass through 25 carburetter 13', 42', 16', 46'' and out through stack 75. Air blasting is continued by varying the air blasting as at 20a, 20b, 20c and 27 by opening and controlling the valves at these levels as desired and also for effecting secondary combustion in the carburetting and regenerating chambers as before described, until the fuel bed and chambers 55 are heated to the desired temperature, when steaming is again resumed with the steam superheated in regenerator 16' as previously described.

Each regenerating chamber is accordingly heated by the blast gases and used for preheating air during alternate blasting periods and each is alternately used for superheating steam during alternate gas making periods.

The regenerators 16' and 16a' preferably contain preheated air offtake zones as 44a with 70 valved outlet 54'' for connection into preheated air distributing pipe 56' to avoid cooling the upper mass of heat absorbing material by the air so the heat therein is conserved for superheating the steam to a relatively higher temperature. 75

In Figures 10 and 11 a plant is shown similar to that in Figures 8 and 9 with the generator partly in section and having an additional valved gas outlet 51a to permit the withdrawal of gas from the annular space 24 and with the carburetting gas superheating chamber 13 omitted and corresponding changes.

Air and steam admission to the generator is carried on as described for Figures 8 and 9. A portion or all or none of the blue gas may be withdrawn through the carbonizing chamber and outlet 51 with the coal gas and vapors mixed therewith, any remaining portion being discharged through gas outlet 51a.

15. The generator in all the combinations may be operated as described for Figure 1 and the two regenerators shown in Figures 8, 9, 10 and 11 in which each is used for preheating air and superheating steam may be used with the plants shown 20 in Figures 1, 2, 6 and 7 instead of the separate steam superheater 15 and air preheaters 16 and 16a.

The separate steam superheater and air preheater as shown in Figures 1, 2, 6 and 7 are preferably used when the highest practicable degree 25 of superheat in the steam is desired and when air is admitted to the generator during the gas making period as at level 20. The steam superheating chamber has a blanketing effect as the steam entering this chamber may be at a higher pressure than the air in the air preheating chambers and prevents any air leaking through the valves as 42 and 42a, entering the carburetting chamber and mixing with the gas therein.

35. With the use of two regenerators each for superheating steam and preheating air, a higher degree of superheat may be obtained in the steam by providing a sufficiently large and long passage of heat absorbing material to permit taking the 40 preheated air from an intermediate point in each chamber as 54" in Figure 8, thus avoiding the cooling action of the air on the hottest portion of the heat absorbing material 44 and conserving the heat therein for superheating the steam 45 to a relatively higher temperature.

The economies and advantages of the different features of my invention will be apparent to those skilled in the art from the foregoing description and may be briefly outlined as follows.

50. The carbonizing chamber and the assembly therein are so constructed and used that the present usual difficulties due to the sticking and hanging of the fuel are overcome and the coal gases and hydrocarbons recoverable in liquid form are recoverable at controllable temperatures with a controllable admixture therewith of other gases.

The heat and time for carbonizing the fuel are substantially reduced over present usual methods.

60. The production of ammonia is favored by the introduction of steam in the carbonizing chamber with the temperatures therein controllable within the optimum limits for ammonia formation.

65. The different features are all combined to provide methods for the production of gas at relatively high rates in apparatus of a given size with a minimum consumption of fuel, air, steam and time.

70. Having described my invention, I claim:

1. The improvement in the manufacture of water gas which, when carried out in a generator having a lower incandescent fuel zone and an upper carbonizing fuel zone and an apertured distillation assembly located in the upper por-

tion of the carbonizing zone, includes: blasting the lower zone of fuel to incandescence with air and withdrawing the resultant products from the upper portion of said zone; alternately with the air blasting, generating water gas by admitting steam to said lower zone of fuel; devolatilizing the fuel in the lower portion of the carbonizing zone by passing steam upwardly therethrough during air blasting periods and also by passing water gas upwardly therethrough during the gas runs; and conducting the steam and the water gas, each admixed with gas liberated from the fuel, upwardly through said apertured assembly and simultaneously drawing into the admixed steam and gas, vapors and gases distilled from the fuel in the upper portion of the carbonizing zone.

2. The improvement in the method of manufacturing water gas from bituminous fuel in a generator having a lower incandescent fuel chamber and an upper carbonizing chamber in open and direct communication with each other and wherein means having a vertical central passage therethrough and vents in the sides thereof, is disposed within the carbonizing chamber with the lower portion of said means positioned a substantial distance above the bottom of the carbonizing chamber, which consists in: alternately air and steam blasting the incandescent fuel to generate water gas and passing the hot water gas from the incandescent fuel upwardly through that portion of the fuel in the lower portion of the carbonizing chamber located below said means and thence into said means both directly into the bottom thereof and also through the sides thereof and withdrawing the hot water gas admixed with products of distillation from the top of said means without the water gas contacting the cooler fuel in the upper portion of said carbonizing chamber.

3. The improvement in the method of manufacturing water gas from bituminous fuel in a generator having a lower incandescent fuel chamber and an upper carbonizing chamber in direct communication with each other and wherein stationary means having a vertical central passage therethrough and vents in the sides thereof, is disposed within the carbonizing chamber with the lower portion of said means positioned above the bottom of the carbonizing chamber and which consists in: alternately air and steam blasting the incandescent fuel to generate water gas and passing hot water gas from the incandescent fuel directly to and upwardly through the fuel in the lower portion of the carbonizing zone and thence into said means through the bottom and side openings thereof and, during the alternate air blasting periods, passing a portion of the air blast gases similarly through the fuel in said lower portion of the carbonizing chamber and thence into said means and withdrawing both the hot water gas and blast gas admixed with the products of distillation from the top of said means without the water gas and blast gas contacting the cooler fuel in the upper portion of the carbonizing chamber.

4. In the manufacture of water gas from carbonaceous fuel in a generator wherein the fuel descends successively through a carbonizing chamber and an incandescent fuel chamber subjected to alternate up-blasting of air and steam for the generation of water gas, the improvement which consists in: confining the fuel in its passage through the carbonizing zone to a column of approximately annular form; during

- the air-blasting periods, heating said fuel column by passing blast gases vertically upward along one of the sides of said fuel column but out of contact therewith; and, during the steam-blast-
5 ing periods, passing generated water gas into the lower portion of said fuel column and up-
wardly thereof on the opposite side of said fuel column to effect distillation thereof and, simulta-
10 neously with said upward passage of the water gas, withdrawing laterally from said fuel column in the carbonizing chamber, the evolved products of distillation progressively at vertically spaced intervals along that side of said fuel column along which the water gas is passed.
- 15 5. In the manufacture of water gas from bituminous fuel in a generator wherein the fuel descends first through a carbonizing zone and thence into an incandescent zone wherein the fuel is alternately up-blasted with air and
- steam to produce water gas, the improvement which consists in: maintaining the fuel, in its passage through the carbonizing zone, between perforate and imperforate confining walls in a column of substantially annular form of gradu-
5 ated increasing cross section from top to bottom thereof; during the air-blast periods, pass-
ing blast gas upwardly of said column of fuel alongside the imperforate confining wall there-
of; and, during the steam periods, passing gen-
10 erated water gas into the lower portion of said fuel column and upwardly alongside the perforate confining wall thereof and creating a partial vacuum in said fuel column and thereby with-
drawing laterally and progressively at points 15 along the perforate wall, the products of dis-
tillation evolved in said fuel column.

HIRAM J. CARSON.
